(57) **CLAIM**

We claim the ornamental design for an applicator head with dosing aid, as shown and described.

DESCRIPTION

FIG. 1 is a perspective view of an applicator head with dosing aid;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines shown in FIG. 7 illustrate portions of the applicator head with dosing aid that form no part of the claimed design.
